UNITED STATES PATENT OFFICE

GUSTAV F. KRAFT, OF KANSAS CITY, MISSOURI

CONDIMENT HOLDER

Application filed June 20, 1928. Serial No. 286,840.

The present invention relates to condiment holders, and aims to provide a novel and improved device of the combined salt and pepper box type, having removable salt and pepper containers, and a closure element adapted to form a closure for either or both of said containers.

Accordingly, I have devised a construction comprising a pair of containers adapted to be removably held in position with their upper ends embraced by a housing member having a continuous web portion extending lengthwise between and the full length of the containers, and having provision for detachably securing a base member to the lower end of the web member. In the preferred form of the construction, the base member cooperates with the top or housing portion for retaining the receptacles in assembled relation.

With the foregoing object in view, the invention will now be described by reference to the accompanying drawings illustrating one form of the improved construction which I have devised for embodying the invention, after which those features and combinations deemed to be novel will be set forth and claimed.

In the drawings—

Figure 1 is a view in elevation illustrating a condiment holder constructed in accordance with my invention;

Figure 1a is a similar fragmentary view illustrating the upper or closure portion of the device, looking at the same at right angles to the plane of Figure 1;

Figure 2 is a plan view of the device;

Figure 3 is a central vertical sectional view taken on the line III—III of Figure 2;

Figure 3a is a fragmentary sectional view, similar to the top portion of Figure 3, but illustrating the closure element partly turned for unclosing one set of the shaker openings;

Figure 4 is a transverse section taken on the line IV—IV of Figure 1;

Figure 5 is a vertical sectional view, representing a section on the line V—V of Figure 3; and

Figure 6 is a transverse section taken on the line VI—VI of Figure 3.

Referring now to the drawings in detail, this illustrates the improved construction as comprising a pair of salt and pepper containers 10 of duplicate form, of substantially semi-circular cross section, but tapering longitudinally downward as represented in Figure 3. The containers are adapted to be held in assembled relation between a base member 12 and an upper or housing portion 14 of upwardly tapered form and adapted to fit over the upper ends of the containers 10 by means of a marginal flange portion 14'. The interior of the housing member 14 is divided by a web 30 into a pair of outlet chambers 15 adapted to be brought into communication with the upper ends of the containers, each of said compartments 15 being provided with a set of shaker outlet openings 16 for which a closure element comprising an approximately conical casing 17 is provided, having a set of shaker openings 18 for each set of openings 16. The closure element 17 is secured in position by means of a cap screw 20 threaded into the upper end of the housing member 14, a coil spring 22 being fitted within a shallow recess 23 about the shank of the screw 20 (as represented in Figures 3 and 3a) for retaining the closure element in yielding frictional engagement with the outer face of the housing 14.

The lower margin of the closure element 17 is provided at diametrically opposite points with a finger-engaging projection 25 for convenience in manipulating the closure element for the purpose of bringing either of the sets of openings 16—17 into register, according to the container from which it is desired to shake the contents. The openings 18 of the closure element 17 are so related to the openings 16 of the housing member that the closure element may be turned into a position for closing both sets of openings 16 as represented in Figure 3, or for opening either of said sets of openings 16 while maintaining the other set closed, as represented in Figure 3a. Preferably, a small opening 27 is provided in the closure element 17 adjacent to each of the finger projections 25 for exposing an index mark such as the letters P and S, standing for the words "pep-

per" and "salt" respectively, which will be exposed through said openings 27, according to the registering positions of the openings 16-18. A detent element 28 on the inner face 5 of the closure member, riding in a short channel 29 formed in the adjacent face of the housing 14, serves to limit the movements of the closure member,—see Figure 5.

The central web 30 forming the partition 10 between the chambers 15 within the housing member 14 is extended on down lengthwise and the full length of the containers 10 as indicated at 30' to form a partition member between the same, as illustrated in Figures 15 1 and 3, the lower end of the extension 30' serving as a means for detachably securing the base member 12, as represented in Figure 3. For this purpose the lower end of the web extension 30' is formed with a pair of notches 20 or recesses 32 for retaining engagement with a pair of ribs 34 provided within the recess 35 in the top of the base member 12, the notches 32 being brought into engagement with said ribs 34 by insertion of the lower 25 end of the web extension 30' through the diametrically opposite recesses 36 between the ribs 34, as shown in Figure 6; after which a partial turn of the base member secures it in retaining relation with the web 30' with 30 the lower ends of the containers 10 seated within the top of the base member, as shown in Figure 3.

Preferably, a slight shoulder formation 37 is provided at opposite sides of the web 35-30' for engagement with the inside straight edges of the containers in order to prevent any of the contents from sifting down between the web and the containers.

The lower end of the web extension 30' 40 also carries a leaf spring element 40 fitted within a central opening 41 and having the ends of said spring 40 engaging and seating within shallow grooves 42 provided in the bottom of each of the containers 10. This 45 structure prevents any loose play in the parts after being assembled, and also guards against any lateral shifting tendency of the containers (relative to the base 12) by virtue of the spring 40 engaging the grooves 42.

50 It will thus be seen that I have provided a very neat, attractive as well as useful and efficient construction for carrying out the desired objects of the invention. The construction is such as is adapted to be embodied in 55 an attractive and ornate design, simulating a single shaker unit, while at the same time possessing all the advantages of a shaker device having two separate compartments for holding two different kinds of condiments.

60 While I have illustrated and described what I now regard as the preferred form of construction for embodying the invention, I desire to reserve the right to make all such changes or modifications as may fairly fall 65 within the scope of the appended claims.

Having thus described my invention, what I claim and desire to secure by Letters Patent is:

1. A condiment holder comprising a pair of containers, a housing member having a discharge compartment for each of said containers, an extension from said housing member projecting between said containers, and a base member detachably fitted to the lower end of said extension and embracing the lower ends of both containers, the upper portion of said extension being formed with shoulders fitting over the upper inner margins of the containers to prevent sifting of the contents down between the extension and containers. 70

75 2. A condiment holder comprising a pair of containers, a housing member having a discharge compartment for each of said containers, an extension from said housing member projecting between said containers, a base member detachably fitted to the lower end of said extension and embracing the lower ends of both containers, and a spring carried by the lower end of said extension, the lower ends of said containers being formed with grooves having retaining engagement with the ends of said spring. 80 85

In witness whereof I hereunto affix my signature. 90
